BIRTH RECORD SPOON

Louis Zuckerman, 234 Reed Road, Wooster, Ohio

Filed Aug. 13, 1958, Ser. No. 52,197

Term of patent 14 years

(Cl. D54—12)

Fig. 1 is a plan view of the birth record spoon of the present invention; and

Fig. 2 is a partial side sectional view of the birth record spoon of Fig. 1.

The dominant features of my design are shown in full lines.

I claim:

The ornamental design for a birth record spoon, substantially as shown and described.
